FREDREK BAUSCHTLEKER AND BARNET VANFLEET, OF WASHINGTON,
DISTRICT OF COLUMBIA.

Letters Patent No. 70,068, dated October 22, 1867.

IMPROVEMENT IN PUMPS.

The Schedule referred to in these Letters Patent and making part of the same.

TO ALL WHOM IT MAY CONCERN:

Be it known that we, FREDREK BAUSCHTLEKER and BARNET VANFLEET, of the city and county of Washington, and District of Columbia, have invented a new and improved Pump; and we do hereby declare the following to be a full, clear, and exact description of the same, reference being had to the accompanying drawings, forming part of this specification, and in which—

Figure 1 is a vertical section of my invention through the line xx of fig. 2.

Figure 2 is a horizontal section of the same through the line yy of fig. 1.

Similar letters of reference indicate corresponding parts in the two figures.

This invention consists in a new valve which clears itself of gravel and other obstructions, and a new box which works more easily and with less liability to injury than those hitherto in use.

The particular difficulties which my invention is designed to obviate are those already referred to, viz, the liability of the valves to become obstructed, and thereby injured and sometimes entirely destroyed, and the fact that in packing the boxes to prevent the escape of air between them and the walls of the pump, they have to be made in general with air-bands or grooves around their periphery, into which the gravel frequently works, interfering with the operation of the boxes, and often causing irremediable injury. To obviate these difficulties we have invented our improved pump.

In order that others skilled in the art to which our invention appertains may be enabled to make and use the same, we will proceed to describe it in detail.

In the drawings, A represents the walls of our improved pump, B the box, and R the pump-rod. The periphery of the box we make perfectly smooth, without external air-bands, and grinding it to a perfectly tight joint with the bore of the pump. Inside of the box B are several air-bands or grooves aa in the walls of the box, communicating through the walls of the box with the outside by means of perforations cc . D D' are the pump-valves, the former attached to the box, the latter to the pump A. Each valve is made of two leaves $d d'$ hinged together along a line running diametrically across them, seating downward and opening upward. The rod s, upon which the valve-leaves hinge as above described, projects beyond the edges of the valves slightly, as shown at ee , forming arms on each side, which extend into a short vertical groove, ii , in the walls of the box or pump, as may be the case. This gives the whole valve an opportunity to slide up and down in the box or pump a distance equal to the length of the slots or grooves ii .

In the operation of this improved pump three important results are attained: First, if by any chance any obstruction should get in under the valve D or D', it will be immediately thrown out by the operation of the valve, which will give way and allow the obstruction to escape, and then immediately return to its proper position. Secondly, no gravel can lodge and remain between the walls of the box and the pump, for as soon as it has insinuated itself between them it will be drawn into the holes cc , and discharged into the interior of the box. And, thirdly, as no packing of rubber, &c., is required in a box of this construction, it will be far cheaper and more durable, besides working more easily than those pumps which are constructed with boxes surrounded by rubber rings, avoiding not only the complication of the parts, but the great friction which always results from the application of rubber packing.

Having thus described our invention, what we claim as new, and desire to secure by Letters Patent, is—

1. The pump-box B, having a smooth exterior, and provided with perforations cc and internal annular grooves aa , substantially as and for the purpose specified.

2. The combination of the valve, having the two leaves and the projections, with the vertical slots or grooves ii , in the interior walls, substantially as and for the purpose described.

To the above specification of our improvement we have signed our hands this 7th day of August, 1867.

FREDREK BAUSCHTLEKER,
BARNET VANFLEET.
